Primary Examiner — Kimberly Barnes
Assistant Examiner — Sarah A Nguyen(57) **CLAIM**

The ornamental design for a cyclonic dust collector, as shown and described.

DESCRIPTION

FIG. 1 is a perspective view of a cyclonic dust collector showing our new design;

FIG. 2 is another perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines shown in the figures depict portions of the cyclonic dust collector that form no part of the claimed design.
